United States Patent Office

Des. 206,871
Patented Feb. 7, 1967

206,871

MOBILE HOME

Glenn R. Thomas and Charles E. Kerr, both of 3010 Military, Oklahoma City, Okla. 73106

Filed Apr. 25, 1966, Ser. No. 1,994

Term of patent 14 years

(Cl. D14—3)

FIG. 3

The dominant features reside in the solid line portions. We claim:

The ornamental design for a mobile home, substantially as shown and described.
